UNITED STATES PATENT OFFICE.

GEORGE H. LOKER, JR., OF ST. LOUIS, MISSOURI.

RIBBON-SHIELD FOR TYPE-WRITING MACHINES.

SPECIFICATION forming part of Letters Patent No. 398,837, dated March 5, 1889.

Application filed March 1, 1888. Serial No. 265,854. (No model.)

To all whom it may concern:

Be it known that I, GEORGE H. LOKER, Jr., a citizen of the United States, residing at the city of St. Louis, State of Missouri, have invented a certain new and useful Improvement 5 in Type-Writing Machines, of which the following is a full, clear, and exact description.

My invention relates to an improvement in that class of type-writing machines known as 10 "The Hammond Type-Writer," and has for its object to prevent the blurring or soiling of the paper caused by the deposit of ink from the ribbon onto and about the edges of the hole formed through the ribbon-shield for the 15 passage of the impression-hammer, which forces the paper against the shield and type.

It consists in the application to the ribbon-shield, between it and the ribbon, of a plate or plates, bar, ring, or other elevated surface, 20 of metal or other suitable material, arranged parallel with the ribbon-shield at each side of, or surrounding the edges of, the hole in the shield, so as to form a depression thereat, by which arrangement the ribbon is prevented 25 from coming in contact with the edges of the hole and adjacent parts of the shield, and the deposit of ink thereon consequently avoided.

On the accompanying drawings, Figure 1 represents a plan of the ribbon-shield and adjacent parts, broken away, of an ordinary 30 Hammond type-writer; Fig. 2, an end view thereof; Fig. 3, a perspective view of the type-wheel guard with my improved ribbon-shield applied thereto; Fig. 4, a front elevation of the improved ribbon-shield to an enlarged 35 scale; and Fig. 5 a section thereof on line 11 in Fig. 4, like letters of reference denoting like parts in all the figures.

a represents the ribbon-shield, which is carried by the base of the type-wheel guard *b*

and arranged horizontally between the ribbon *c* and paper *d*.

e is the type-wheel, and *f* the catch; *g*, the impression-hammer, and *h* and *i* the ribbon-spools and guide-screws, respectively, all these 45 parts being located and operating in the usual well-known manner.

According to a preferable mode of carrying out my invention, I solder or otherwise attach to the ribbon side or face of the shield *a* 50 two plates, *k*, of equal thickness, which are located one on each side of the hammer-hole *j* and extend horizontally some way along and parallel with the shield *a*. The inner ends of the plates *k*, which are at a suitable distance 55 from and parallel with the vertical side edges of the hole *j*, may extend entirely across the shield *a*, by which arrangement a vertical slot or depression, *l*, is formed between the shield *a* and ribbon *c* immediately opposite and adjacent to the hammer-hole *j*, so that while the ribbon *c* is thereby enabled to make contact 60 between the type-wheel and paper in the act of printing it is prevented by the plates *k* from touching the edges of the hole *j* in the shield 65 *a*, and so soiling the paper, as is the case at present.

I claim—

A type-writer ribbon-shield having a hammer-hole with elevated surfaces at the sides 70 of the hammer-hole, so as to form a depression thereat, substantially as described, and for the purpose specified.

In testimony whereof I affix my signature, in presence of two witnesses, this 25th day of 75 February, 1888.

GEORGE H. LOKER, JR.

Witnesses:

S. L. SCHRADER,
PAUL BAKEWELL.
